UNITED STATES PATENT OFFICE.

CHARLES K. BRADFORD, OF LYNNFIELD, MASSACHUSETTS.

APPARATUS FOR CEMENTING THE CHANNELS OF BOOT OR SHOE SOLES.

SPECIFICATION forming part of Letters Patent No. 278,086, dated May 22, 1883.

Application filed March 8, 1883. (No model.)

To all whom it may concern:

Be it known that I, CHARLES KEMPTON BRADFORD, a citizen of the United States, residing at Lynnfield, in the county of Essex and State of Massachusetts, have invented 5 certain new and useful Improvements in Machines for Cementing Channels in Boot or Shoe Soles; and I do hereby declare the following to be a full, clear, and exact description of the invention, such as will enable others skilled in the art to which it appertains to make and use the same, reference being had to the accompanying drawing, and to letters or figures of reference marked thereon, which form a part of 15 this specification.

This device is intended to perform the labor of smearing with cement the channels of boot or shoe soles; and it consists of a device containing the following elements: a reservoir 20 to contain the cement for smearing the channel, and an air-pump for charging the fountain-brush for applying the cement to the channel of a sole, connected with the interior of the cement-reservoir by a flexible pipe to permit 25 of freedom of motion of the brush in any direction.

The drawing accompanying this specification represents a sectional elevation of a device embodying my invention.

30 In said drawing, A represents a reservoir or tank in the form of an upright can, erected or supported upon a suitable base, B, this can being intended to contain a quantity of cement suitable for cementing the channels of boot and 35 shoe soles, this can, when supplied with cement, being never entirely filled, in order that an air-space may remain above its contents.

C represents an air-pump of any ordinary 40 construction, the same communicating with the upper part of the can A by a pipe, D, in order that the space a above the cement may be filled with compressed air from the pump, a cock, b, being placed in the pipe D for the purpose of relieving the pipe D from effects of 45 pressure, and preventing leakage of air from the can by way of the pump. At the bottom of the pipe D, I have placed an air-drum, F, provided with a check-valve, f, to facilitate the process of pumping and lessen the chances 50 of leakage and back flow of air upon the pump.

E in the drawing represents a flexible pipe,

one end of which communicates with the lower part of the can A, while its opposite end is furnished with a fountain-brush, c, for distribution of the cement from the can. 55

In the operation of this device the can is supplied with the requisite quantity of cement—say about five-sixths full—and the cock b opened. The operator now operates the 60 pump C and fills the upper part of the can with compressed air to the desired pressure, and closes the cock b. The operator now seizes the brush, which is constantly supplied with cement from the can by the pressure of air in 65 the latter, and proceeds with the operation of smearing the channels of boot or shoe soles until his labor for the time is completed, when he closes a cock, d, in the pipe E and shuts off the flow of cement to the brush. As the 70 can becomes exhausted of its supply of cement it is to be refilled and the operation of supplying air repeated.

Heretofore in the operation of cementing the channels of boot or shoe soles it has been 75 customary for the operator to simply employ an ordinary brush, which he from time to time dips into a vessel of cement and transfers cement from the latter to the channel. In this manner of proceeding the operation is 80 comparatively lengthy and inconvenient, and considerable cement is spilled about and wasted.

By means of my device the labor of cementing channels is performed with expedition, ease, and economy, and no cement is spilled or 85 wasted. A secondary cock, e, may be located to the rear of the brush and further regulate the supply of cement thereto when in active operation.

I claim—

90 In an apparatus for cementing the channels of boot or shoe soles, or other analogous purposes, the combination, with a reservoir for holding the cement, of an air-pump arranged to charge the reservoir above the cement with 95 compressed air, a flexible pipe for conveying the cement, and a fountain-brush, all arranged substantially as shown and described.

In testimony whereof I affix my signature in presence of two witnesses.

CHAS. KEMPTON BRADFORD.
